UNITED STATES PATENT OFFICE

JOSHUA H. STREET, OF CHATTANOOGA, TENNESSEE

SLACKLINE EXCAVATOR

Application filed June 11, 1928. Serial No. 284,625.

This invention relates to a slackline excavator, one of the objects being to provide an excavator which includes a carriage mounted to travel along a supporting rope and carrying a bucket stick or beam mounted for swinging movement, there being a novel arrangement of cables for swinging the bucket relative to the carriage for the purpose of digging into and removing a portion of the soil, 5 conveying the bucket and carriage to a point of delivery, and then delivering the contents of the bucket.

A further object is to provide a means whereby the track rope or cable can be payed 15 out or drawn taut to lower or to elevate the bucket so as to bring it into proper position for excavating and thereafter lift it to a point where it can be actuated to convey the load to the point of discharge.

20 Another object is to provide an excavator of this type which can be operated readily and used for handling material over an extensive area.

With the foregoing and other objects in 25 view which will appear as the description proceeds the invention resides in the combination and arrangement of parts and in the details of construction hereinafter described and claimed it being understood that changes 30 in the precise embodiment of the invention herein disclosed may be made within the scope of what is claimed without departing from the spirit of the invention.

In the accompanying drawing, which is a 35 side elevation of the complete apparatus, parts being broken away, the preferred form of the invention has been shown.

Referring to the drawing by characters of 40 reference 1 designates a track cable on which is supported a carriage 2 which includes a connecting beam or frame member 3. A bucket 4 of the ordinary steam shovel type has a beam 5 fixedly connected to it, this beam being pivotally connected to the carriage as 45 indicated for example at 5'. A latch lever 6 is pivotally connected to one end portion of the carriage and has a chain 7 or other flexible means for transmitting motion therefrom to the latch 8 which normally holds the bucket 50 closed. Another latch lever 9 is carried by

the other end portion of the carriage and is coupled by a rod 10 or the like to the latch lever 6, the two latch levers and their connections being so assembled that when either latch lever has its upper end pressed inwardly 55 away from the adjacent end of the carriage, the connection 7 will pull on the latch 8 and allow the bucket to dump its contents.

A hoist mechanism has been indicated generally at 11 and includes three independently 60 operated drums 12, 13, and 14. The track cable 1 is fastened at one end to the drum 12 and is extended over a sheave 15 suitably supported, as by means of an upstanding structure 16. This track cable is extended above and longitudinally of the area to be excavated and the far end of the cable is fixedly attached, as at 17, to another supporting structure 18. An outhaul cable 19 is fastened at 65 one end to the drum 14 and is extended over a sheave 20 on the structure 16 and thence longitudinally over the area to be excavated to another sheave 21 carried by the structure 18. From this last sheave the outhaul is extended 70 back and fastened to the carriage 2 as shown at 22. A third cable 23 which constitutes both 75 a backhaul and a bucket operating cable is fastened to the drum 13 and is extended over a sheave 24 carried by the structure 16. This cable constitutes part of a block and tackle 80 connection between the carriage 13 and the bucket 4 as indicated at 25.

In using this excavating mechanism the track line or cable 1 is drawn taut by winding it on the drum 12 and as the slack is taken out of this cable the carriage and the parts supported thereby will of course be elevated. By taking up the cable 19 on drum 14 the carriage can be hauled back to a point above 85 where the excavation is to start, it being understood that the cable 23 is also payed out during this movement of the carriage. Thus the bucket 4 will be held suspended in its uppermost position and when it is brought to the point of starting the excavation the bucket is lowered into contact with the soil by paying out the track cable 1 so that it will sag sufficiently to bring the bucket to the desired level.

Following the operation just described the 90 cable 23 is taken up by winding it on the 95 100

drum 13 and this will cause the bucket 4 to swing forwardly and upwardly about the pivot 5, the advancing edge of the bucket digging into the soil and directing it into the bucket. When the bucket reaches an elevated position near the top of the carriage the track cable 1 is drawn taut to elevate the carriage and its load and thereafter, by pulling on the cable 23, or by pulling on the outhaul cable 19 while the cable 23 is held taut, the carriage can be moved either forwardly or backwardly until it arrives at a point where the load is to be discharged. At that time one of the latch levers 6 will come against a tripping projection 26 previously placed at the point where the discharge is to be effected. As soon as the latch lever strikes this projection which is on the track lever 1 the connection 7 will pull on the latch 8 and release the load from the bucket 4 which will of course be delivered by gravity. The carriage can then be brought back to its starting position, the bucket lowered so that its closure will shut automatically, as ordinarily, and the operation already described can then be repeated.

It will be obvious that by providing apparatus such as described, an excavating operation extending over a considerable area can be carried on easily and quickly.

23. What is claimed is:

1. A slackline excavator including a track cable, a carriage mounted to travel therealong, a bucket connected to and suspended from the carriage, means for swinging the bucket relative to the carriage to fill the bucket and elevate the load, said means constituting a means for shifting the carriage in one direction along the track cable, means for shifting the carriage in the opposite direction along said cable, cooperating means on the carriage and track cable for discharging the load from the bucket when the carriage is brought to a predetermined position on the cable, and means for paying out the track cable to lower the carriage and bucket and for taking up said cable to elevate the carriage and bucket.

2. A slackline excavator including a track cable, a carriage mounted to travel thereon and provided with an elongated beam, a beam pivotally connected to and suspended from the carriage, an excavating bucket fixedly connected to the pivoted beam, and separate cables for shifting the carriage longitudinally of the track cable and for swinging the pivoted beam relative to the carriage beam.

3. A slackline excavator including a track cable, a carriage mounted to travel thereon and provided with an elongated beam, a beam pivotally connected to and suspended from the carriage, an excavating bucket fixedly connected to the pivoted beam, and separate cables for shifting the carriage longitudinally of the track cable and for swinging the

pivoted beam relative to the carriage beam, a latch carried by the bucket, connected latch levers on the carriage oppositely connected to the latch on the bucket, and means on the track cable cooperating with the latch levers to shift the bucket latch and discharge the contents of the bucket.

4. A slackline excavator including an elongated carriage, a track cable for supporting the same, a beam pivotally connected to and descending from one end portion of the carriage, a bucket fixedly connected to and movable with the lower end portion of the pivoted beam, and means connecting the shovel to the other end portion of the carriage for shifting the pivoted beam and its shovel relative to the carriage without changing the angle of the shovel relative to the pivoted beam.

5. A slackline excavator including an elongated carriage, a track cable for supporting the same, a beam pivotally connected to and descending from one end portion of the carriage, a bucket fixedly connected to and movable with the lower end portion of the pivoted beam, and means connecting the shovel to the other end portion of the carriage for shifting the pivoted beam and its shovel relative to the carriage without changing the angle of the shovel relative to the pivoted beam, said means constituting a means for shifting the carriage along the track cable in one direction, and cooperating means on the carriage and track cable for automatically dumping the contents of the bucket on reaching a predetermined position.

In testimony that I claim the foregoing as my own, I have hereto affixed my signature.
